ELECTRIC CONTROL SYSTEM

Edgar N. Halliday, Chicago, Ill.

Application July 9, 1931, Serial No. 549,791

15 Claims. (Cl. 88—17)

The invention relates to electric control systems especially adapted for use in controlling the operation of moving picture machines, the primary object of the invention being the provision of a simple and effective electrical control system of the character indicated, which is capable of economical production and highly efficient in use.

Another object of the invention is the provision of a control system of the character indicated, especially adapted for use in conjunction with moving picture films or the like which could be readily damaged by sparking and so constructed and arranged as to eliminate all danger of sparking in operating the control circuits.

15 Other objects of the invention will appear hereinafter.

The invention consists in the combinations and arrangements of parts hereinafter described and claimed.

20 The invention will be best understood by reference to the accompanying drawings forming a part of this specification, and in which:

Figure 1 is a diagrammatic view of electrical circuits and co-operating parts embodying the 25 invention;

Figure 2, a similar view showing the positions of the parts in a later stage of operation;

Figure 3, a similar view showing the relative 30 positions of the parts in a still later stage of operation; and

Figure 4, a similar view showing the relative positions of the parts in a still later stage of operation.

The embodiment of the invention illustrated 35 in the drawings comprises two motion picture machines illustrated diagrammatically as 10 and 11 in the drawings and each operating upon and co-operating with the usual moving picture film 12 or 13, as indicated. The film 12 carries two 40 longitudinally spaced electrical switch members 14 and 15 in the form of short lead pencil lines on the film, as indicated, and the film 13 is provided with two corresponding and similar electric switch members 16 and 17.

45 Co-operating with the films 12 and 13 are four primary control circuits 18, 19, 20 and 21 including, respectively, the contact members 22, 23, 24 and 25, so set with relation to the films 12 and 13 as to co-operate, respectively, with the 50 switch members 14, 15, 16 and 17 to close the corresponding primary circuits when said switch members pass in co-operative relationship with said contacts, as will be readily understood.

Included, respectively, in the circuits 18, 19, 20 and 21 are four grid glow control tubes, each

comprising a grid 30, an anode 31 and a cathode 32 connected as indicated. Each of said primary circuits also includes an electro-magnet 33. The arrangement is such that as each switch member 14, 15, 16 and 17 passes the corresponding pair of contacts 22, 23, 24 or 25, the grid of the corresponding glcw tube is grounded, whereby the corresponding circuit 18, 19, 20 or 21 is operated to excite the corresponding magnet 33, the character of the grid glow tube being such as to have this effect without any sparking or other material electrical disturbance, as will be readily understood by those skilled in this art.

Associated with the respective primary circuits 18, 19, 20 and 21 are four secondary control circuits 34, 35, 36 and 37 including, respectively, spring-held magnetic switches 38, 39, 40 and 41, co-operating with the electro-magnet 33 in the corresponding primary circuit and whereby, when the corresponding primary circuit is closed, as explained above, the corresponding magnetic switch will be operated to close the corresponding secondary circuit, as will be readily understood by those skilled in this art.

Each of the said secondary control circuits 25 also includes an electro-magnet 33 which co-operates, respectively, with spring-held switches 42, 43, 44 and 45 so arranged that when each secondary circuit is closed, the corresponding magnet 33 will be excited to operate the corresponding switch.

30 Co-operating with each of the said secondary control circuits is a corresponding branch circuit 46, 47, 48 and 49 leading from its corresponding secondary circuit from such a position therein that the corresponding magnet 33 will be excited when the corresponding branch circuit is closed, irrespective of what happens later to the corresponding secondary control circuit. Each of said branch circuits also includes an independent 35 electro-magnet 33, as indicated.

The switch 42 is a double switch carrying two 40 switch contact members 50 and 51. The contact member 50 is included in a circuit 52 which includes an electro-magnet 33 co-operating with a switch member 54 arranged to close the operating circuit 55 for the moving picture machine 11, so that when the secondary circuit 34 or the branch circuit 46 is closed, the switch 42 will be 45 operated to close the circuit 52 and thereby cause operation of the machine 11. It is also to be noted that concurrently with the closing of circuit 52, the branch circuit 46 will be closed 50 through an electro-magnet 33 and a manual 55

switch 46', thereby exciting the corresponding magnet 33.

Co-operating with the magnet 33 in circuit 46 is a spring-held switch 56 adapted and arranged to control a circuit 57, said circuit 57 being the circuit which operates the arc light for machine 11.

The switch 43 carries two switch contacts 58 and 59, the former controlling a circuit 60 and the latter controlling the corresponding branch circuit 47, as shown. The circuit 60 is the circuit which operates or controls the operation of the sound mechanism for the picture machine 11 so that, when the corresponding secondary circuit 15 35 or branch circuit 47 is closed, the circuit 60 will also be closed for operation of the sound for the machine 11. The switch 43 also carries a switch contact 61 controlling the branch circuit 49 from secondary control circuit 37, as indicated, 20 and so that when circuits 47 and 60 are closed, the circuit 49 will be opened.

Co-operating with the electro-magnet 33 in the branch circuit 47 is a spring-held switch 62 carrying a contact 63 controlling a circuit 64, the circuit 64 being the circuit which controls or operates the shutter or automatic cut-out for the light for the machine 11 so that when branch circuit 47 is closed, the light for machine 11 will be established. Switch 62 also carries a switch contact 65 included in secondary control circuit 35, so that when circuits 47 and 64 are closed, secondary control circuit 35 will be broken.

Co-operating with the magnet 33 in branch circuit 48 is a spring-held switch 66 controlling circuit 67 which is the circuit controlling or operating the arc light for the machine 10, so that when branch circuit 48 is closed, circuit 67 will also be closed and the light for machine 10 established.

The switch member 44 carries two contacts 68 and 68', contact 68 controlling a circuit 69 and contact 68' controlling the branch circuit 48. Circuit 69 includes an electro-magnet co-operating with the switch 70 which controls the operating circuit 71 for machine 10 so that when branch circuit 48 is closed, the operating circuit 71 for machine 10 is also closed and the operation of machine 10 begun.

Co-operating with the electro-magnet 33 in the branch circuit 49 is a spring-held switch 72 controlling a circuit 73 which is the operating or controlling circuit for the automatic light shutter for the light of the machine 10 and whereby when circuit 73 is closed, said light is established.

Switch 45 carries two contacts 74 and 75 controlling, respectively, the circuits 76 and 49. Circuit 76 is the circuit which operates or controls the sound for the machine 10 so that, when closed, the sound for the machine 10 is established. Switch 45 also carries a switch contact 77 controlling branch circuit 47 so that when circuit 76 is closed, branch circuit 47 is broken.

All of the circuits are supplied with current, as indicated, from a supply circuit 78.

In operation, with the parts in the positions indicated in Fig. 1, in which positions the film 13 has just passed beyond the contacts 24 and 25, the film 12 will be in full operation. The film 13 is at once removed from the projecting machine 11 and a new film 13 substituted for it. Sometime, also, during the operation of film 12 and prior to the passage of the extreme end thereof through the contacts 22 and 23, the manual switch 48' in the branch circuit 48 is closed.

Then, when the switch member 14 passes into

co-operative relationship with the contacts 22, the primary control circuit 18 will be grounded, thereby unbalancing and actuating the tube 26 to permit flow of sufficient current in circuit 18 to excite the corresponding magnet 33, thereby closing switch 38. The flow of current through the circuit 18 is so small and the resistance of the pencil mark switch 14 is so great that there will and can be absolutely no sparking when circuit 18 is made or broken. This permits use of the apparatus in conjunction with moving picture films or other inflammable objects without danger of fire. Closing the switch 38 closes secondary control circuit 34 through the corresponding electromagnet 33 which operates to close circuits 46 and 52. Closing of circuit 52 starts the operation of projecting machine 11 for the commencement of the operation of the newly inserted film 13. At the same time, branch circuit 46 is closed, thereby exciting the corresponding magnet 33 to 20 close switch 56 which closes circuit 57 so that the arc circuit 51 for the light or arc for machine 11 is operated to establish the arc and thereby place the newly inserted film 13 in operation.

It is to be noted that the branch circuit 46 leads from the circuit 34 from a position beyond the magnet 33 so that the circuit 46 will itself operate to keep itself and the circuit 52 closed, notwithstanding the almost immediate breaking of circuit 34 due to the passage of the switch member 14 beyond the contacts 22.

As soon as the switch member 15, through the continued operation of the film 12, closes the primary control circuit 19, the secondary control circuit 35 will be closed to excite electro-magnet 33, thereby closing branch circuit 47 and control circuit 60. The closure of control circuit 60 starts the operation of the sound mechanism of machine 11 and, at the same time, circuit 48 is broken, opening circuits 73 and 76 and closing circuit 41. The opening of circuit 73 closes the light shutter for machine 10, thereby extinguishing the same, and the opening of circuit 76 stops the sound mechanism for machine 10, as indicated in Fig. 3.

The operation of machine 10 continues until film 12 completely passes therethrough, whereupon the switch 48' is opened to break the circuit 48, thereby also opening circuits 67 and 69, as indicated in Fig. 3.

The opening of circuit 67 extinguishes the arc for machine 10. Opening circuit 69 stops machine 10 and the opening of circuit 73 closes the light shutter for machine 10.

A new film 13 is now substituted for the film 12 and switch 48 closed to prepare the system for continued operation.

In the meantime, as explained above, the machine 11 is in complete operation and so continues until the end of the film comes to the contacts 24 and 25, whereupon the operations above described are repeated in conjunction with film 13 as they were for film 12. Thus, when switch member 16 passes into co-operative relationship with the contacts 24, primary circuit 20 is grounded to close secondary circuit 36, thereby closing circuits 67 and 69. The closing of circuit 67 starts the arc for machine 10 and the closing of circuit 69 starts the motor for machine 10, thus starting the operation of film 12, as indicated in Fig. 4.

Then when switch member 17 passes into co-operative relationship with the contacts 25, primary circuit 21 is grounded to close secondary circuit 37, thereby closing circuits 73 and 76 and breaking circuit 41. Closing of circuit 73 opens

the light shutter for film 12 of machine 18 and closing of circuit 76 starts the operation of the sound mechanism for machine 18 and film 12. Breaking the circuit 47 opens circuits 68 and 64, 5 thus placing the parts in condition for repeating the above cycle of operation, as indicated in Fig. 1.

In this manner, the two light projecting machines will be automatically controlled, each by the film of the other, so that there will be no perceptible interruption in the performance as the change is made from one film to another. It is also to be noted that there will be no sparking or other material electrical disturbance when the change is made so that the system may be safely employed in conjunction with moving picture film or other inflammable elements.

While I have illustrated and described the preferred form of construction for carrying my invention into effect, this is capable of variation and modification without departing from the spirit of the invention. I, therefore, do not wish to be limited to the precise details of construction set forth but desire to avail myself of such variations and modifications as come within the scope 25 of the appended claims.

I claim:

1. The combination of two primary control circuits each including a switch operating magnet; two secondary control circuits each including a switch operable by one of said magnets; a grid glow control tube in each of said primary circuits; a moving picture projector including a traveling moving picture film carrying longitudinally spaced means for unbalancing and there- 35 by actuating said tubes in succession to actuate said primary circuits to actuate said switches to actuate said secondary circuits; and separate operating circuits operable by said secondary circuits and arranged to cause actuation of desired 40 instrumentalities.

2. The combination of two primary control circuits each including a switch operating magnet; two secondary control circuits each including a switch operable by one of said magnets; a grid glow control tube in each of said primary circuits; a moving picture projector including a traveling moving picture film carrying longitudinally spaced means for grounding the grids of said tubes in succession to unbalance and thereby actuate said primary circuits to actuate said switches to actuate said secondary circuits; and separate operating circuits operable by said secondary circuits and arranged to cause actuation of desired instrumentalities.

3. The combination of four primary control circuits arranged in two co-operating pairs each including a switch operating magnet; four secondary control circuits each including a switch operable by one of said magnets; a grid glow control tube in each of said primary circuits; two moving picture projectors including traveling moving picture films each carrying longitudinally spaced means for unbalancing and thereby actuating one pair of said tubes in succession to actuate the corresponding pair of primary circuits to actuate the corresponding pair of switches to actuate the corresponding pair of secondary circuits; and separate operating circuits for each of said projectors operable by said secondary circuits.

4. The combination of four primary control circuits arranged in two co-operating pairs each including a switch operating magnet; four secondary control circuits each including a switch operable by one of said magnets; a grid glow control tube in each of said primary circuits; two

moving picture projectors including traveling moving picture films each carrying longitudinally spaced means for grounding the grids of one pair of said tubes in succession to unbalance and thereby actuate the corresponding pair of primary circuits to actuate the corresponding pair of switches to actuate the corresponding pair of secondary circuits; and separate operating circuits for each of said projectors operable by said secondary circuits.

5. The combination of four primary control circuits arranged in two co-operating pairs each including a switch operating magnet; four secondary control circuits each including a switch operable by one of said magnets; a grid glow control tube in each of said primary circuits; two moving picture projectors including traveling moving picture films each carrying longitudinally spaced means for unbalancing and thereby actuating one pair of said tubes in succession to 20 unbalance and thereby actuate the corresponding pair of primary circuits to actuate the corresponding pair of switches to actuate the corresponding pair of secondary circuits; separate operating circuits for each of said projectors operable by said secondary circuits; a branch circuit leading from each of said secondary circuits at a point to cause, when closed, excitation of the corresponding secondary circuit magnet; a magnet in each of said branch circuits; a control circuit including a switch operable by each branch circuit magnet; and means on each switch in each secondary circuit for simultaneously closing the corresponding branch circuit.

6. The combination of four primary control circuits arranged in two co-operating pairs each including a switch operating magnet; four secondary control circuits each including a switch operable by one of said magnets; a grid glow control tube in each of said primary circuits; two moving picture projectors including traveling moving picture films each carrying longitudinally spaced means for grounding the grids of one pair of said tubes in succession to unbalance and thereby actuate the corresponding pair of primary circuits to actuate the corresponding pair of switches to actuate the corresponding pair of secondary circuits; separate operating circuits for each of said projectors operable by said secondary circuits; a branch circuit leading from each of said secondary circuits at a point to cause, when closed, excitation of the corresponding secondary circuit magnet; a magnet in each of said branch circuits; a control circuit including a switch operable by each branch circuit magnet; and means on each switch in each secondary circuit for simultaneously closing the corresponding branch circuit.

7. The combination of two moving picture projecting machines, each including a traveling picture film; electric circuits for operating said machines; switch contacts in each of said circuits; and two longitudinally spaced successively operating electric switch members on each film, each preceding switch member controlling the switch contacts in the circuit for the other machine and each succeeding switch member controlling the switch contacts in the circuits for both machines.

8. The combination of two moving picture projecting machines each including a traveling picture film; electric circuits, including a switch, for operating said machines; four primary control circuits each including a switch operating magnet; a secondary control circuit for each primary control circuit and including a switch oper-

able by the magnet in the corresponding primary circuit and also including a magnet operable for controlling the machine operating circuits; and two longitudinally spaced successively operating electric switch members on each film, each preceding switch member controlling the switch in the primary circuit for the other machine and each succeeding switch member controlling the switch in the primary circuit for the corresponding machine.

9. The combination of a primary control circuit including a switch operating magnet; a secondary control circuit including a switch operable by said magnet; a grid control tube in said primary circuit; a mechanism and cooperating flexible destructible band-like traveling member movable endwisely, said mechanism operating on and causing travel of said member; an operating circuit for said mechanism; means operable by said secondary circuit for controlling said operating circuit; and means on said traveling member for unbalancing and thereby actuating said tube to actuate said primary circuit to actuate said switch to actuate said secondary circuit.

10. The combination of a primary control circuit including a switch operating magnet; a secondary control circuit including a switch operable by said magnet; a grid control tube in said primary circuit; a moving picture projector including a traveling moving picture film; an operating circuit for said projector; means operable by said secondary circuit for controlling said operating circuit; and means on said film for unbalancing and thereby actuating said tube to actuate said primary circuit to actuate said switch to actuate said secondary circuit.

11. The combination specified in claim 10 in which the unbalancing of the grid is effected by grounding the same.

12. A primary control circuit including a switch operating magnet; a secondary control circuit including a switch operable by said magnet and also a second switch operating magnet; a double switch operable by said second magnet; an operating circuit operable by said double switch; a first mechanism connected for operation by said operating circuit; a branch circuit including said double switch and leading from said secondary control circuit at a point to cause, when closed, excitation of said secondary magnet; a magnet in said branch circuit; a second operating circuit including a switch operable by said last mentioned magnet; a second mechanism connected for operation by said second operating circuit; and means for closing said primary control circuit.

13. The combination specified in claim 12, in which the first mechanism includes a traveling member operated on and caused to travel thereby and the means for closing the primary control circuit is carried by said traveling member.

14. The combination specified in claim 12 in which the first mechanism includes a traveling member operated on and caused to travel thereby, the primary circuit includes a grid glow tube and the means for closing the primary control circuit is carried by the traveling member and arranged to unbalance said tube.

15. The combination specified in claim 12 in which the first mechanism includes a traveling member operated on and caused to travel thereby, the primary circuit includes a grid glow tube and the means for closing the primary control circuit is carried by the traveling member and arranged to unbalance said tube by grounding the same.

EDGAR N. HALLIDAY.
